UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE CONSTRUCTION.

Application filed March 9, 1923. Serial No. 623,841.

My invention relates to electrical receptacle construction, and more particularly to a husk socket construction.

One of the objects of my invention is to provide a husk socket construction in which a sub-assembly including an insulating base and receptacle contact is readily attachable and detachable with respect to the enclosing husk without the use of tools.

10 A further object of my invention is to provide a husk socket construction which will be cheap to manufacture and durable and efficient in use.

15 A further object of my invention is to provide a husk socket interior which can be readily attached and detached with respect to either a straight husk, or an angle husk.

Further objects will appear from the detailed description to follow and from the appended claims.

In the drawings in which two embodiments of my invention are shown—

20 Fig. 1 is a part sectional, part elevational view of a husk socket;

Fig. 2 is a part sectional, part elevational view at right angles to Fig. 1;

Fig. 3 is a section on the line 3—3 of Fig. 1;

30 Fig. 4 is a top plan view of the interior of the husk socket;

Fig. 5 is a bottom view of Fig. 4;

Fig. 6 is a plan view of an insulating washer;

35 Fig. 7 is a section on the line 7—7 of Fig. 4;

Fig. 8 is a section on the line 8—8 of Fig. 4;

Fig. 9 is a sectional view showing an angle 40 husk socket construction;

Fig. 10 is a sectional view showing the way the supporting members and fibre cap are secured inside the husk; and

Fig. 11 is a section on the line 11—11 of Fig. 4.

Referring now to the drawings in detail, the husk socket construction shown therein comprises a husk 10, a sub-assembly comprising an insulating base 11, a threaded shell contact 12, a center contact 13, a switch mechanism 14 and binding screws 15 and 16 all mounted on said base, and an insulating fibre sleeve or cup 17, surrounding the threaded shell contact 12, and means for detachably securing the sub-assembly in the husk, com-

prising a pair of spring arms 18, embracing the insulating base 11, and extending down into the space between the insulating sleeve 17 and the lower portion of the husk 10, in position where they can be engaged by the 60 finger and thumb, to push the spring arms 18 outwardly away from each other, and away from the insulating base 11, to release the insulating base 11 from engagement with the spring arms 18, to permit the removal of the 65 sub-assembly.

The spring arms 18 may be formed as parts of an integral sheet member stamping, the central portion of which is rigidly secured to a nut 19, which is threaded onto the 70 threaded nipple 20, on which the husk 10 is mounted. The husk 10 is clamped between the shoulder 21 of the nipple 20 and the nut 19 which carries the spring arms 18.

The engagement between the spring arms 75 18 and the sub-assembly is effected by providing the spring arms with notches 22, to receive lugs 23 on the insulating base 11. The insulating base 11 is provided with grooves 24 in its sides, to receive the spring 80 arms 18. An insulating fibre cap or cover 25 is provided above the insulating base 11, to cover up the binding screws 15 and 16, and the ends of the wires connected thereto. This fibre cap or cover is secured to the 85 spring supporting arms 18 by providing diametrically opposed notches in the fibre cap, to receive the spring arms, the spring arms themselves being provided with shoulders at 26, to hold the fibre cap up in place. 90

The manner of securing the spring arms and fibre caps in place in the husk 10 is indicated in Fig. 10 which shows a spanner wrench 27, having wrench engaging fingers 28, which can be inserted through the diametrically opposed openings 29 (Fig. 6) in the fibre cap 25, and engaged with the opposite sides of the nut 19, which carries the spring arms 18. By turning the spanner wrench 27, the nut 19 is screwed onto the 100 threaded nipple 20 to secure the spring arms in the husk 10, and to secure the husk 10 on the nipple 20.

The switch mechanism 14 mounted on the insulating base 11, may be of any suitable 105 construction provided with a pull chain 30 which extends down inside the husk 10, and between the lamp 31 and the shade 32, which is secured to the husk 10.

This switch mechanism 14 controls the cir- 110

cuit between the binding screw 16 and the center contact 13.

In a general way, when the switch is in on position the circuit is from the binding screw 16, through the conducting and clamping plate 33, (Figs. 4 and 8), spring contacts 34 and 35, (Figs. 8 and 11), rotatable contact 36, switch bracket 37, and eyelet 38 to the center contact 13. When the switch 10 is in off position, the circuit is broken at two points in series, substantially simultaneously, one break being between the spring contacts 34 and 35, the other being between the spring contact 35 and the rotatable contact 36. The spring contacts 34 and 35 are insulated from each other by a fibre disc 38^a (Figs. 8 and 11).

The binding screw 15 is always electrically connected with the shell contact 12 through 20 the binding plate 39 and the conducting screw 40.

In assembling the construction, the sub-assembly comprising the insulating base 11, the receptacle contacts 12 and 13, the switch 25 mechanism 14, the wiring terminals 15 and 16 and the insulating sleeve 17, is first assembled as a unit; the fibre cap 25 is slipped into place between the spring arms 18, the husk 10 is placed in position on the nipple 30 20, the nut 19 carrying the spring arms 18 and the fibre cap 25 is screwed onto the nipple 20 by means of the spanner wrench 27, and the sub-assembly referred to is then slipped into place in the husk 10, between 35 the spring arms 18, these spring arms being sprung outwardly until the lugs 23 are in position to enter the notches 22 in the spring arms, whereupon the spring arms will spring toward each other, the lugs 28 entering the notches 22 and the sub-assembly being firmly 40 held in position between the spring arms.

To release the sub-assembly, all that is necessary to do is to reach up between the insulating sleeve 17 and the skirt portion of 45 the husk, and spread the spring fingers 18 apart sufficiently to free the lugs 23 from their engagement with the spring arms, whereupon the whole sub-assembly can be readily drawn down and out of the husk. 50 This removal of the sub-assembly is effected simply by reaching in and grasping the insulating sleeve 17, taking care that the thumb and finger are inserted between the insulating sleeve 17 and the spring arms 18, so the mere insertion of the thumb and finger 55 in position to grasp the sleeve, forces the spring fingers outwardly.

The construction shown in Fig. 9 is substantially the same as that just described, 60 except that here the spring arms 18 are formed of a sheet metal stamping which is secured to the angle husk by means of an eyelet or rivet member 41, which also serves as a closure and ornamental finish for the 65 upper portion of the husk. As shown in

Figs. 1, 3 and 7, the insulating base is so constructed that it can be used either for the straight socket shown in Fig. 1, or for the angle socket shown in Fig. 9, the insulating base being recessed on one side, as 70 indicated at 42, to provide clearance for the wires in case an angle husk is used, and being recessed on top as indicated at 43 to provide ample clearance for the wires in case the straight socket is used as shown in 75 Figs. 3 and 7.

While I have shown but two forms of my invention, it is obvious that it may be embodied in other forms covered and defined by the appended claims. 80

This application is a continuation as to common subject matter claimed herein of my co-pending applications, Serial No. 311,983, filed July 18, 1919, and Serial No. 324,832, filed September 19, 1919. 85

Having thus described my invention, what I claim as new and desire to secure by United States Letters Patent, is:

1. An electrical receptacle construction comprising a sub-assembly including (1) an insulating base; (2) a threaded shell contact mounted thereon; and (3) a sleeve surrounding said threaded shell contact; a husk enclosing said sub-assembly and surrounding said sleeve and spaced therefrom, said 90 husk extending downwardly substantially as far as the lower edges of said sleeve and shell contacts, and means for detachably securing said sub-assembly in said husk, comprising means accessible to the hand of the operator between said husk and sleeve for detaching the sub-assembly, said securing means comprising a pair of spring arms secured adjacent the top of the husk and extending down alongside said base, on opposite sides thereof, and extending below said insulating base into the space between the sleeve and the husk, in position to be engaged by the hand of the operator, the space between the husk and sleeve adjacent 110 the ends of the spring arms being unobstructed and there being sufficient space between the sleeve and the ends of the spring arms to permit the ready insertion of the thumb or finger, whereby the spring arms 115 are forced outwardly in the act of grasping the sleeve to release the sub-assembly from the spring arms.

2. An electrical receptacle construction comprising a sub-assembly including (1) an insulating base; (2) a threaded shell contact mounted thereon; and (3) a sleeve surrounding said threaded shell contact; a husk enclosing said sub-assembly and surrounding said sleeve and spaced therefrom, said 120 husk extending downwardly substantially as far as the lower edges of said sleeve and shell contacts, and means for detachably securing said sub-assembly in said husk, comprising means accessible to the hand of the 125 130

operator between said husk and sleeve for detaching the sub-assembly, said securing means comprising a pair of spring arms secured adjacent the top of the husk and extending down alongside said base, on opposite sides thereof, and extending below said insulating base into the space between the sleeve and the husk, in position to be engaged by the hand of the operator, said insulating base and spring arms being provided with interengaging means for holding said base between said arms, the space between the husk and sleeve adjacent the ends of the spring arms being unobstructed and there being sufficient space between the sleeve and the ends of the spring arms to permit the ready insertion of the thumb or finger, whereby the spring arms are forced outwardly in the act of grasping the sleeve to release the sub-assembly from the spring arms.

3. An electrical receptacle construction comprising a sub-assembly including (1) an insulating base; (2) a threaded shell contact mounted thereon; and (3) a sleeve surrounding said threaded shell contact; a husk enclosing said sub-assembly and surrounding said sleeve and spaced therefrom, said husk extending downwardly substantially as far as the lower edges of said sleeve and shell contacts, and means for detachably securing said sub-assembly in said husk, comprising means accessible to the hand of the operator between said husk and sleeve for detaching the sub-assembly, said securing means comprising a pair of spring arms secured adj-

acent the top of the husk and extending down alongside said base, on opposite sides thereof, and extending below said insulating base into the space between the sleeve and the husk, in position to be engaged by the hand of the operator, said spring arms and insulating base having interengaging shoulders whereby said base is held between said arms, the space between the husk and sleeve adjacent the ends of the spring arms being unobstructed and there being sufficient space between the sleeve and the ends of the spring arms to permit the ready insertion of the thumb or finger, whereby the spring arms are forced outwardly in the act of grasping the sleeve to release the sub-assembly from the spring arms.

4. A husk socket construction comprising a nipple, a husk supported on said nipple, a non-circular wrench-engaging bushing inside the upper end of said husk and threaded on said nipple, a receptacle sub-assembly comprising (1) an insulating base and (2) a shell contact mounted thereon, said sub-assembly being insertable into said husk through the outer end thereof, means mounted on said bushing for securing said sub-assembly in place in the husk and an insulating cover carried by said bushing between the insulating base and the upper end of the husk, having openings therein for the passage of a wrench to engage the non-circular wrench-engaging portion of the bushing.

In witness whereof, I have hereunto subscribed my name.

REUBEN B. BENJAMIN.
